PORTABLE PAPER MICROMETER

Adolph J. Semeneck, Oak Lawn, Ill., assignor to
William Y. Chatterton, River Forest, Ill.

Application December 19, 1949, Serial No. 6,705

Term of patent 14 years

(Cl. D52—1)

To all whom it may concern:

Be it known that I, Adolph J. Semeneck, citizen of The United States of America, residing at Oak Lawn in the county of Cook and State of Illinois, have invented a new, original, and ornamental Design for a Portable Paper Micrometer, of which the following is a specification, reference being had to the accompanying drawing, forming part thereof, and in which,

Fig. 1 is a top view of a portable paper micrometer, showing my new design,

Fig. 2 is a side elevational view thereof, and

Fig. 3 is an elevational view taken from the right side of Fig. 2.

The side of the micrometer not shown is substantially the same in appearance as the side shown.

I claim:

The ornamental design for a portable paper micrometer, substantially as shown and described.

ADOLPH J. SEMENECK.
